UNITED STATES PATENT OFFICE

171,986

TOY FAN

Curtis F. Pearl, Teaneck, N. J., assignor to Keller Corporation, Brooklyn, N. Y., a corporation of New York

Application October 12, 1953, Serial No. 27,147

Term of patent 14 years

(Cl. D34—15)

To all whom it may concern:

Be it known that I, Curtis F. Pearl, a citizen of the United States, residing at Teaneck, in the county of Bergen and State of New Jersey, have invented a new, original, and ornamental Design for a Toy Fan, of which the following is a specification, reference being had to the accompanying drawing, forming part thereof.

In the drawing

Fig. 1 is a front elevational view of a toy fan, showing my new design;

Fig. 2 is a side elevational view thereof; and Fig. 3 is a rear elevational view.

I claim:

The ornamental design for a toy fan, substantially as shown.
